FIG. 5

UNITED STATES PATENT OFFICE.

EDMUND L. HAZARD, OF HOLLISTER, IDAHO.

WRENCH.

1,407,152.

Specification of Letters Patent. Patented Feb. 21, 1922.

Application filed March 3, 1921. Serial No. 449,514.

To all whom it may concern:

Be it known that I, EDMUND L. HAZARD, a citizen of the United States, residing at Hollister, in the county of Twin Falls and 5 State of Idaho, have invented certain new and useful Improvements in Wrenches, of which the following is a specification.

This invention relates to improvements in quick adjusting wrenches.

10 The primary object of the invention is the provision of a rapid adjusting wrench, in which the associated parts are cooperatively designed, to permit an operator to proximately move the jaws thereof into engagement with an object with a thumb or finger of the same hand used to hold the wrench.

15 A further object of the invention is the provision of a wrench of the above described character, which is simple in construction, 20 well balanced, durably constructed to absorb forces or strains due to action on a piece of work, and which includes convenient means of adjustment.

25 Other objects and advantages will be apparent during the course of the following detailed description.

In the accompanying drawing forming a part of this specification, and in which similar reference characters designate corresponding parts throughout the several 30 views:

Figure 1 is a plan view of the improved wrench.

35 Figure 2 is a side elevation of the improved wrench showing the hand of an operator in dotted lines, and the means for quickly adjusting the wrench to move the jaws into proximate relation.

40 Figure 3 is a fragmentary enlarged cross sectional view showing the jaw supporting and adjusting means.

Figure 4 is a cross sectional view taken on the line 4—4 of Figure 3.

45 Figure 5 is a cross sectional view taken on the line 5—5 of Figure 2.

In the drawing, wherein for the purpose of illustration is shown the preferred embodiment of my invention, the letter A designates a jaw ordinarily called the rigid 50 jaw of a wrench; B, a movable jaw, and which is reciprocable with respect to jaw A; C, a handle structure rigid with jaw A; and D, the jaw supporting and adjusting means associated with the improved wrench.

55 The stationary jaw A comprises the jaw head 10, having the jaw gripping face 11

on the under surface; and having integrally formed upon one side of said under surface 11, a pair of spaced shanks 12 and 13. The shanks 12 and 13 are of substantially 60 the same cross section, and are smaller in cross section than the head 10 upon which they are cast or otherwise formed. The shank 12 is provided with a depression or recess 15, on the inner face thereof, and 65 facing the space 16 provided intermediate the shanks 12 and 13, and the purpose of which recess 15 and space 16 will hereinafter be specifically mentioned.

The handle C, includes the side plates or 70 pieces 20 and 21, of similar formation, and which are attached to the shanks 12 and 13 upon the ends thereof opposite the wrench head 10, as by pins 22 or the like. The plates 20 and 21, are provided with outer 75 rounded surfaces 23, adapted for convenient formation to an operator's hand. Said side plates 20 and 21 are so attached to the shanks 12 and 13 as to leave the space 16 intermediate said shanks unobstructed, and in fact 80 providing a pocket 24 in the handle C. The side plates 20 and 21 are of sufficient length to terminate short of the end of the recess 15, thus leaving a majority of said recesses 85 forming a part of the pocket 24.

The movable jaw B comprises the jaw head 26, of substantially the same width of the jaw head 10, and which is provided with the article engaging face 27. This jaw 26 is symmetrically disposed with respect to the 90 jaw 10, and has suitable apertures 28 and 29 therein for the reception of the shanks 12 and 13 respectively. The jaw head 26 is relatively longer than the jaw head 10, and the rearwardly projecting end 30 faces the 95 handle structure C, the same being of the same width as the rest of the jaw 26, providing the rear surfaces 31 to be engaged by the thumb of an operator, for a purpose to be subsequently set forth. A shank 35 is 100 formed integrally upon the rear of the projection 30 and which shank 35 is in effect a ratchet bar of the same width and substantially the same cross section as the shanks 12 and 13, said ratchet bar 35 in reality being operatively and reciprocably disposed within the space 16 provided intermediate 105 said shanks 12 and 13. Teeth 36 are provided upon a side surface of the ratchet bar 35, said teeth being inclined rearwardly toward the handle structure C and provided with the rounded upper faces 37. In posi-

tion the movable jaw B is so disposed with respect to the jaw A that the teeth 36 face the recess 15. The ratchet bar 35 is of sufficient length to allow reciprocation of the 5 jaw B with respect to jaw A, and in order to provide an operating association of parts, the bar 35 projects for a short distance into the pocket 24.

The means D which permits quick adjustment of jaw B with respect to jaw A; and maintains said jaw B in rigid position when a desired adjustment is secured; includes the pawl 40, and the spring 41. The pawl 40, is an elongated structure, including the head 15 42, on the under surface of which are formed a plurality of teeth 43, said teeth being forwardly inclined and adapted for engaging the spaces intermediate teeth 36 upon the ratchet bar 35. Said pawl 40 is provided 20 upon the rear end thereof with a suitable aperture for the reception of a pin 44, said pin 44 being supported by the side plates 20 and 21, in order to pivotally mount the pawl 40 within the recess 15 in the shank 12. The 25 head 42 of the pawl thus projects from the pocket 24 provided intermediate the side plates 20 and 21, said head having finger or thumb pieces 45 laterally projecting from each side thereof and spaced a sufficient distance to operate comfortably with respect to the shank 12, when the wrench structure 30 is assembled.

The outer faces 46 of the thumb pieces 45 are rounded, and may be knurled, for securing a better grip thereupon. The spring 41 is provided with the rear end 42 thereof seated within a depression in the shank 12 and which spring 41 forwardly projects and overlies the top of the elongated pawl 40, 40 for normally maintaining the teeth 43 thereof in firm engagement with the teeth 36 of the ratchet bar 35.

The structure is so assembled, that the thumb pieces 45 laterally project forwardly 45 of the handle structure C and upon each side of the shank 12, thus placing them in convenient position to the hand of an operator of the wrench. In order to move the jaw B rearwardly with respect to the jaw A, 50 the operator has merely to place his thumb and index finger upon the thumb piece and finger piece 45, and pulling upwardly thereon rock the pawl 40 upon its pivot pin 44, and against normal action of the spring 41. 55 This releases the teeth 43 from engagement with the teeth 36, and the jaw head 26 and ratchet bar 35 can be rearwardly moved, and the ratchet bar 35 inserted in the pocket 24.

When the approximate space intermediate 60 the operating faces 11 and 27 of the jaw heads 10 and 26 respectively has been reached, the object to be worked upon is placed intermediate said jaw faces, and as is usually the case, the space intermediate the 65 jaw faces is more than enough to accommo-

date the object worked upon. In order to take up this discrepancy, the operator uses the same hand with which he holds the wrench and engages the end surface 31 of the projection 30 with the tip of his thumb, 70 and the jaw's head 26 can be pushed forwardly by slight pressure until the jaw faces 11 and 27 engage the work to be operated upon. This adjustment is mainly permitted by reason of design of the teeth 36 75 and 43, since upon forward movement of the jaw B with respect to the jaw A, the teeth 43 of the pawl 40 ride over the curved upper faces 37 of teeth 36, and against normal action of the spring 41. However, due to the 80 action of said spring the pawl normally finds its place in proper engagement with the ratchet bar teeth, when the desired adjustment of the jaws has been secured.

Various changes in the shape, size and 85 arrangement of parts, may be made to the form of the invention herein shown and described, without departing from the spirit of the invention or the scope of the claims.

I claim:

1. A wrench comprising in combination a jaw head, a pair of spaced shanks connected to said jaw head, a second jaw head reciprocably mounted upon said shanks, a ratchet bar rigid with said second jaw head, 95 and a pawl pivotally mounted on one of said shanks for co-operation with said ratchet bar to regulate adjustment of said second jaw head.

2. A wrench comprising in combination 100 a jaw, a shank thereon including a hand engaging portion, a second jaw movable with respect to said shank and first mentioned jaw and operatively disposed intermediate the first mentioned jaw and the hand engaging portion, a ratchet bar on said second jaw having teeth thereon inclined away from second jaw, and a pawl engaging said teeth for holding said second jaw to prevent movement away from said first jaw and permitting proximate movement of said jaws.

3. A wrench, comprising in combination a jaw head, a pair of spaced shanks connected to said jaw head, a second jaw head reciprocably mounted upon said shanks, side 115 grips upon said shanks forming a double handle structure, and means interposed with said shanks to regulate adjustment of said second mentioned jaw head, said means including a ratchet, bar rigid upon said second jaw, a 120 pawl pivoted in said handle and normally in engagement with said ratchet, and projecting finger pieces for releasing said pawl.

4. A wrench comprising in combination 125 a jaw head, a pair of spaced shanks rigid with said jaw head, a second jaw head reciprocably mounted upon said shanks, a handle mounted rearwardly upon said shanks, a ratchet bar rigidly mounted to said second jaw head, and placed between said shanks, 130

and a pawl for said ratchet bar pivoted in said handle, the teeth and pawl so positioned as to permit proximate movement of said jaws, and preventing retraction with respect to each other.

5. A wrench comprising in combination 10 a jaw head, a pair of reduced spaced shanks rigid thereupon, a second jaw head substantially the same in width as said first mentioned jaw head, and having apertures there- in to be reciprocably disposed upon said first mentioned jaw shanks, side pieces rigid upon the ends of said shanks rearwardly of said first mentioned jaw head, and providing a

15 pocket structure intermediate said shanks, a ratchet bar having rearwardly inclined teeth thereon rigid with said second mentioned jaw head and disposed intermediate said shanks and in said pocket, a pawl for said ratchet bar pivoted in said pocket, and 20 to the side pieces of said handle, said pawl having a plurality of teeth formed centrally thereon, means normally maintaining said teeth in engagement with the teeth upon said ratchet bar, and finger pieces formed 25 rigid upon said pawl, and laterally projecting forwardly of said handle structure.

EDMUND L. HAZARD.
